(57) **CLAIM**

The ornamental design for a mobile communication device, as shown and described.

DESCRIPTION

FIG. 1 is a front perspective view of a mobile communication device showing our design;

FIG. 2 is a front view thereof;

FIG. 3 is an opposing rear view thereof;

FIG. 4 is a side view thereof;

FIG. 5 is an opposing side view thereof;

FIG. 6 is a bottom view thereof; and,

FIG. 7 is a top view thereof.

The broken lines shown herein are for illustrative purposes only and form no part of the claimed design.
